CLAIM

The ornamental design for a diskette holder, as shown and described.

DESCRIPTION

FIG. 1 is a front elevational view of a diskette holder showing my new design;

FIG. 2 is a rear elevational view thereof;

FIG. 3 is a side elevational view thereof, the opposite side being a mirror image;

FIG. 4 is a top plan view thereof;

FIG. 5 is a bottom plan view thereof; and,

FIG. 6 is a perspective view thereof shown in use, the broken lines showing an additional diskette holder being for illustrative purposes only and forming no part of the claimed design.

FIG 1

FIG 2

FIG 4

FIG 5

FIG 3

FIG 6
